R. A. SCHOENBERG, NOW BY JUDICIAL CHANGE OF NAME, R. A. BELMONT.
PIN PLUG CONNECTOR.
APPLICATION FILED JUNE 18, 1917.

1,272,126.

Patented July 9, 1918.

UNITED STATES PATENT OFFICE.

RALPH A. SCHOENBERG, (NOW BY JUDICIAL CHANGE OF NAME RALPH A. BELMONT,) OF NEW YORK, N. Y.

PIN-PLUG CONNECTOR.

1,272,126.

Specification of Letters Patent.

Patented July 9, 1918.

Application filed June 18, 1917. Serial No. 175,249.

To all whom it may concern:

Be it known that I, RALPH A. SCHOENBERG, (now by judicial change of name RALPH A. BELMONT,) of New York, in the county and State of New York, have invented a new and useful Pin-Plug Connector, of which the following is a specification.

The main objects of my invention are to provide a pin plug connector which is simple in construction and cheap to manufacture but very efficient in use.

A feature of my invention is the elimination of the ordinary contacts riveted to the screw shell.

Another feature is the elimination of the threading of the insulating body.

Another feature is the direct contact between the pin and screw shell.

Another feature is having the pin exposed to contact directly with the receiving socket.

Another feature is a spring contact between the screw shell and pin.

Another feature is the use of the insulating body to hold the screw shell in place.

Another feature is the center contact provided with a flange to engage screws of different lengths.

Another feature is the reduction of size and weight which is particularly important in the matter of freight and of custom duties.

Another feature is the member connecting the center contact with one of the pins and having spring flanges to engage said pin.

Another feature is that the body part of the plug will fit the standard receiving member and yet the pin carried by the cap will make a better contact because, among other reasons, it contacts with the shell of the plug and also with the shell of the receiving member.

Another feature is a threaded insulating body to engage the receiving member, one of the pins being exposed to engage the receiving member.

Other features will be pointed out below.

In the drawings:

Figure 1 is a central longitudinal sectional view of a connector embodying my invention;

Fig. 2 is an elevation of the pin-carrying member of the connector shown in Fig. 1;

Fig. 3 is a bottom plan view of the member shown in Fig. 2;

Fig. 4 is a side elevation of the plug member of the connector shown in Fig. 1;

Fig. 5 is a plan view of the plug member shown in Fig. 4;

Fig. 6 is a section on line 6—6 of Fig. 4; and

Fig. 7 is a central longitudinal sectional view showing a modification.

The plug cap member has a base A and split contact pins a a' connected to the lead wires.

The body member B shown in Fig. 1 is of porcelain and has a head b slightly offset so that the standard cap member may be used therewith. Member B is further provided with an aperture b' for passage of pin a, with recesses b², b³, b⁴ and b⁵ for purposes hereinafter described, and with a central hole for the reception of the center contact screw F.

To body member B is applied screw shell D having a lip d bent in to engage the bottom of recess b⁵ to prevent said shell from slipping off of said body, the sides of said lip engaging the side walls b⁶ and b⁷ of the recess b⁵ to prevent rotation of the screw shell with relation to body B. The recess b⁵ opens at the top of member B for convenient insertion if desired of a tool to bend over lip d.

The shell is provided with two curved flanges d' and d² bent inward in recess d⁴ for resilient engagement with pin a which in this form not only directly engages the screw shell but does so at the outside of the shell and is exposed for direct contact with the contact of a socket or other receiving member.

Center contact E is held in place by screw F which also holds in place contact member G which is in recess b² and has a portion bent down into recess b³, the bent portion having two integral resilient curved arms g and g' which directly engage pin a'.

Center contact E has a flat portion e for contact and an integral internally threaded 100 and inwardly extending portion e' to engage screw F, the purpose of the extended threading being that the center contact may be used with screws of different lengths.

In the form of Fig. 7 the insulating body B' is threaded on its exterior for direct mechanical engagement with a socket or other receiving member (not shown). In this form the pin a is exposed for direct electrical engagement with a contact of the receiving member and this engagement is under pressure due in part to the resilience of the pin, this engagement under pressure being substantially the same as that for the pin a in Figs. 1 and 2.

What I claim is:

- 15 1. A pin plug connector comprising an external threaded member having a spring portion; and a pin to engage said spring portion.
2. In combination with a separable pin plug member an insulating body portion carrying a threaded embossed metal contact

member on its periphery for contact with a 20 current carrying terminal of an electric light or other current supply fixture, said contact member also serving as a contact terminal for one of the pins of the pin plug.

3. In combination with a separable pin 25 plug member an insulating body portion carrying a threaded embossed metal contact member on its periphery for contacting with a current carrying terminal of an electric light or other current supply fixture, said 30 contact member also serving as a contact terminal for one of the pins of the pin plug which is located so as to wedge itself between the peripheral metal contacting member of the insulating body portion, and the current carrying terminal of a fixture. 35

RALPH A. SCHOENBERG.
